GRATE STRUCTURE

John W. Hulson, Keokuk, Iowa, assignor to
Hulson Grate Company, Keokuk, Iowa

Application March 22, 1940, Serial No. 325,440

1 Claim. (Cl. 126—180)

The invention relates to grate structures of the general type in which pluralities of fingers are mounted on carrier bars, the fingers being removably held on the bars by interlocking means. In such grates, it is common practice to successively place the fingers on the bar at one point, and to slide said fingers into their proper locked-on positions, the last finger to be applied serving to prevent movement of any of the others to removal position until said last-applied finger is released and removed. With such arrangement, in order that the last-applied finger shall be movable from locked-on position to removal position, it has heretofore been necessary that it have quite an amount of movement longitudinally of the bar, and in order to permit this, it has been required that the various fingers be so spaced apart that abnormal crowding of them together would provide the space necessary for said movement of said last-applied finger to removal position, and the rather wide finger spacing has had a tendency to permit the fingers to group themselves instead of remaining uniformly distributed throughout the length of the bar, resulting in improper distribution of draft air and non-uniform elimination of ash. In tuyère-type grates in which the draft air is baffled to prevent stack loss, cinder cutting and slagging of flues, the prior finger spacing has increased the straight draft area of the grates, and the more such area is increased, the more danger there is of said stack loss, cinder cutting and flue slagging. Moreover, with prior constructions, there has been danger of the locking finger (last finger applied) working up from the finger carrying bar under vibration, particularly when shaking the grates. The present invention, however, aims to provide an improved interlocking means for the fingers and bar which will prevent accidental detachment of the locking finger and will require very little movement of the last-applied finger longitudinally of the bar when it is to be removed and will consequently permit close spacing of the fingers, to the extent of placing them substantially in contact with each other, thereby overcoming prior difficulties.

With the above in view, the invention resides in the novel subject matter hereinafter described and claimed, description being accomplished by reference to the accompanying drawings.

Figure 1 is a side elevation of a portion of a carrier bar and a number of the fingers thereon, showing the normal relation of fingers and bar.

Figure 2 is a view similar to Fig. 1 but showing

most of the fingers crowded together, making room for removal of the first or "key" finger.

Figures 3 and 4 are views similar to Figs. 1 and 2 but showing the movements imparted to the first or "key" finger in order to remove same.

Figures 5 and 6 are vertical sectional views on lines 5—5 and 6—6 of Fig. 1.

Figure 7 is a sectional perspective view showing a portion of the carrier bar.

In the drawings above briefly described, a preferred construction has been illustrated and while this construction will be specifically explained, it is to be understood that variations may be made within the scope of the invention as claimed.

The fingers are shown at 10 and the carrier bar at 11, and while I have shown said fingers provided with tuyères 10' for draft air, the present invention is not concerned with the finger construction except insofar as that construction acts to removably mount the fingers on the carrier bar.

The preferred cross-sectional shape of the carrier bar 11 is that of a heavy squat I-beam with the lower lateral ribs 12 thereof extending uninterruptedly from end to end of the bar. At the top of this bar, however, instead of providing ribs extending continuously from end to end of said bar, I provide each side of the latter with two ribs 13 and 14 having their inner extremities spaced apart to provide the spaces 15 which permit easy removal and application of the fingers 10. The rib 13 is preferably very short and integrally joined at its outer end to one of the vertical finger stop flanges 16 and trunnion 17, while the rib 14 extends from the space 15 to the opposite end of the carrier bar 11. The inner extremity 18 of the rib 14 is preferably vertical but the inner extremity of the rib 13 is of angular form as shown more particularly in Figs. 4 and 7, the upper portion 19 of this rib extremity being slanted upwardly away from the other rib extremity 18, and the lower portion 20 of the rib extremity in question being slanted downwardly away from said extremity 18.

In the present showing, each finger 10 is provided with a hub 21 under its head portion 22, and with vertical webs 23 connecting said hub and head portions, each hub being of a width (measured longitudinally of the bar 11) somewhat less than the width of said head portion. Each hub rests on the bar 11 and is provided with a downwardly open notch 24 receiving said bar, the opposed side walls of the notch being provided with inwardly projecting lugs 25. These lugs

25 of the various fingers 10 normally underlie the ribs 13 and 14 and thus prevent direct lifting of any of the fingers from the carrier bar 11. At this time, one of the endmost fingers 10 has its lugs 25 hooked under the short ribs 13 and has its hub 21 disposed substantially in contact with the stop flange 16 as shown in Fig. 1. Portions of the lugs of this endmost finger of course project under portions of the notches 15 and the same is true of the lugs of the next adjacent finger, all of the fingers being then substantially in contact with each other. The fingers in these relative positions are firmly locked on the carrier bar with no danger of even those adjacent the spaces 15 becoming accidentally detached.

Before any of the fingers can be detached from the carrier bar, it is necessary that all of said fingers, except the one endmost finger engaged with the ribs 13, be crowded together toward the end of the bar opposite the spaces 15. This will leave a slight space 26 (Fig. 2) between said one endmost finger and the rest of the fingers, allowing said endmost finger to be slid toward the others and then tilted as seen in Fig. 4, alining its lugs 25 with the spaces 15 and thus permitting lifting of the finger from the carrier bar. Then, the other fingers may be successively slid to the spaces 15 and vertically lifted from the bar. Due to the bevels 19 and 20 on the inner extremities of the ribs 13, only a very small space 26 is required, one quarter of an inch being sufficient in most instances. This space, after all of the fingers are applied to the bar, is of course distributed throughout the length of the latter, and the various fingers are, therefore, substantially in contact with each other for effective air control and ash elimination. Moreover, the fingers have no tendency to group themselves but remain uniformly distributed throughout the length of the carrier bar.

It will be seen from the foregoing that novel provision has been made for permitting easy removal and application of the fingers to the bar, for effectively interlocking the fingers with the bar, and for permitting easy manipulation of the last-applied or first-removed finger as required, without the necessity of making such provision that the various fingers must be rather extensively spaced with danger of grouping themselves upon the bar.

While preferred details have been disclosed and each side of the carrier bar 11 has been provided with two ribs 13 and 14, it will be obvious that variations may be made and that one side of the bar could be plain if desired, providing the ribs 13 and 14 and the space 15 at the opposite side only of said bar.

What is claimed is:

In a grate structure, a horizontal carrier bar each vertical side of which is provided at the upper edge of said bar with two alined longitudinal ribs and a space between said ribs, one of said ribs at each side of said bar being disposed at one end of the bar and being very short, the other of said ribs at each side of said bar being relatively long, and a plurality of fingers having trivially spaced fire-supporting heads and downwardly projecting portions nearly as wide as said heads, said downwardly projecting portions being spaced apart longitudinally of said bar and having notches receiving the upper portion of the bar, the lower end of one of said downwardly projecting portions having lugs underlying the full length of said short ribs and substantially half the length of said spaces between the ribs, the lower ends of the rest of said downwardly projecting portions having lugs underlying said long ribs and part of the length of said spaces between the ribs, the various lugs normally preventing direct lifting of the fingers from the bar, the inner extremities of said short ribs each having an upper bevel slanted upwardly away from the opposite extremity of the adjacent long rib and also having a lower bevel slanted downwardly away from said opposite extremity of said adjacent long rib, said lower bevels permitting the lugs of one of said fingers to clear said short ribs and underlie said spaces between the ribs when said one finger is inwardly slid slightly and manually rocked about the outer upper corner of its notch after crowding the rest of the fingers together, said upper bevels then permitting said lugs of said one finger to pass through said spaces between the long and short ribs as said one finger is lifted, the whole permitting removal of said one finger with only trivial normal spacing of the various fingers.

JOHN W. HULSON.
